HAT AND CONSTRUCTIONAL ELEMENT
THEREFOR

Sarah B. Roberts, Los Angeles, Calif.

Application September 29, 1947, Serial No. 776,741

4 Claims. (Cl. 2--175)

1

This invention relates to a constructional element for use in making hat-wear, particularly feminine hat-wear, and to hats made therefrom.

Most hats are made from blocked forms, and this is particularly true of hats made from felt, straw, and the like. Other hats are made from various materials, stitched, folded, draped, and otherwise formed to a desired shape. The manufacture of hats requires a tremendous amount of cutting, fitting and forming of odd-shaped pieces or a complicated set of operations whereby woven or felted materials are caused to conform to a desired contour. Feminine head-wear is bulky and requires large, bulky packages or containers when it is desired to carry the same. A woman when traveling is forced to carry large hat boxes in order to have available a change of hats.

The present invention is directed to a constructional element from which various hats may be made. It is also directed to a method of construction and to a resulting hat which can be unpinned and caused to assume an extended, substantially flat form occupying little volume or space. Hats made in accordance with the present invention can therefore be readily packed within a trunk, suitcase, or the like, thus eliminating the necessity of using large, bulky hat boxes.

The constructional element of the present invention may be made from a great variety of materials such as woven straw, cloth fabrics, net, felt, or various combinations of materials. These constructional elements may be suitably decorated, edged or bound. Moreover, the same constructional element may be caused to assume various forms or may be caused to make hats differing widely in appearance.

It is an object of the present invention, therefore, to disclose and provide improvements in the manufacture of feminine head-wear.

It is a further object of the invention to disclose and provide a novel constructional element from which head-wear may be made.

A still further object of the invention is to disclose and provide hats capable of being unfolded or expanded into substantially flat form, thereby facilitating the packing or transportation of hats.

These and various other objects and advantages of the present invention will become apparent to those skilled in the art from the following description of a preferred form of constructional element and of various hats made therefrom. In such description reference will be had to the appended drawings, in which:

2

Fig. 1 is a plan view of a preferred form of constructional element, this view illustrating the element in its expanded, laid out or flat condition.

Fig. 2 is a perspective three-quarter rear view of one form of hat made by the use of the element.

Fig. 3 is a three-quarter front elevation of another form of hat made from the constructional element of this invention.

Fig. 4 is a plan view of a still further form of hat.

Fig. 5 illustrates one position or manner in which the hat of Fig. 4 may be worn.

Figs. 6 and 7 are perspective three-quarter rear and side elevational views respectively, of a still further form of hat made from the constructional element.

The constructional element illustrated in Fig. 1, in extended or flattened form, is substantially S-shaped and provided with rounded ends. This constructional element may be said to have the main body portion 10 and the rounded ends 11 and 12. One of these ends is preferably larger than the other, as indicated. The body portion is S-shaped or sinuous. Both marginal edges of the body portion are in the form of reversed curves. One marginal edge may include the concave marginal section 14 and the convex section 15, this convex section blending into the edge of the rounded end 11. The other marginal edge of the body portion 10 may include the concave section 16 and the convex section 17, the latter blending into the margins of the larger end 12. These two marginal edges of the body portion preferably separate as they approach the larger end 12, thereby imparting to the body portion a progressively increasing width from its neck (adjacent the smaller rounded end 11) to the larger end 12. It will be noted that the concave portions of such marginal edges, such as the portions 14 and 16, merge into and meet the margins of the ends at relatively sharp corners, such as the corners 18 and 19. It may be stated that the enlarged rounded end portions 11 and 12 point in substantially opposite directions and extend from the body 10 toward the concave portions of the adjacent marginal edges.

It may be noted in passing and in the way of an example that the constructional element of Fig. 1 may have a total length of between about 20 and 26 inches, and a maximum width (in the region between point 18 and the outer convex margin) of between 4 and 6 inches.

As previously indicated, the constructional element hereinabove referred to may be made from any desired material. Netting, cloth, straws,

sheets of copolymers, polymerization products and condensation products, and various combinations of materials (normally in sheet form) may be used. The marginal edges of such constructional element may be bound or otherwise decorated. The materials used may be transparent, translucent or opaque, and the entire unit may be lined or unlined. The unit hereinabove described may then be used in making various hats, such as, for example, the hat shown in Fig. 2. Attachment means, indicated at 21 and 22, may be carried by the end portions 11 and 12 respectively on one side of the element. The attachment means 21 may be caused to overlay and be connected with the means 22, giving rise to a hat of the character shown in Fig. 2. It will be noted that the small rounded end 11 now overlaps the large rounded end 12 in the rear of the head of the wearer. It will now be noted that the marginal edges 16 and 17 form the outer edges of the hat, the marginal edge 17 bending downwardly at the rear and then sweeping upwardly to form an upstanding front. A portion of the body of the element is folded upon itself to form the edge 23, the inner marginal edge of the body 14 merging into the edge 15 which at the rear of the hat forms the outer and lower margin of the hat. A decorative bow 24 is shown applied to and covering the juncture of the overlapping ends 11 and 12.

It is to be remembered that the constructional units of the present invention may be made of materials which differ greatly in strength, rigidity, pliability, deformability, etc. The hat may be made of horsehair or relatively stiff but bendable material covered with cloth, satin, or the like, permitting the wearer to fold and bend the hat into any desired configuration.

Similarly, the hat illustrated in Fig. 3 is made of a single constructional element and the marginal edges of the constructional unit utilized in making this hat are shown decorated with a velvet and sequin edging or trim 27. The enlarged end 12 of the constructional unit is indicated at 12' and forms the top of the hat. The outer marginal edge of the unit at a point indicated at 28 in Fig. 1 is connected to such marginal edge at a point located approximately at 29, and the small rounded end portion 11 is then attached to the body at approximately the point 30 to form the hat. The concave marginal edge 16 therefore overlies and traverses the surface of the body 10. Dash lines in Fig. 3 indicate the hat in a partly unrolled condition.

It will be noted that the various means of attachment, such as 21 or 22, or the connections between points 28 and 29, etc., may be either permanent connections or they may be releasable connections such as afforded by means of snap fasteners, etc. Releasable connections are preferred since the entire hat may be readily unrolled and packed for transportation.

Figs. 4 and 5 illustrate a modified form of construction wherein two of the patterns or constructional units are partially stitched together. The two units may be completely stitched together in the region of the neck and small rounded end 11. The marginal edges 16 and 17 may also be stitched together, such stitching extending down to a suitable point on the rear edge of the enlarged rounded end 12. The inner marginal edges 14 are not stitched together but instead are permitted to be separable, as indicated at 14 and 14'. The means of attachment illustrated in Fig. 1 are used in causing the smaller

rounded portion 11 to overlap the larger portion 12. The wearer may then utilize the hat somewhat in the manner of a tam-o-shanter, permitting a portion of her head and hair to extend into the opening between the unstitched marginal edges 14 as shown in Fig. 5.

A sports cap or hood cap may be made from the constructional element illustrated in Fig. 1, the resulting garment being shown in Figs. 6 and 7. As there illustrated, it will be noted that the large end 12 has been stitched to the adjacent marginal edges 14 and 15, the edge 17 now forming the rear and low edge of the hat. The small end 11 is left hanging and may be utilized as a chin strap, particularly when a small end portion of a unit, such as the portion 31, is attached to the opposite side of the hat, as best indicated in Fig. 7. Removable means for connecting the two small end portions 11 and 11' permit the cap to be firmly held upon the head, the portions 11 and 11' meeting beneath the chin of the wearer.

The manufacture of hats by the use of this invention permits shipment of hats from manufacturers to stores in a compact manner, thereby eliminating boxing, the costs incidental thereto, and the difficulties encountered in shipping fragile, easily crushed and deformed articles such as hats.

It will be noted that blocking or the utilization of intricate forms, and other disadvantages incidental to the manufacture of hats in the customary manner are obviated by the use of the constructional element. Those skilled in the art will recognize the tremendous variety of headgear which may be made by the use of this constructional unit. All changes coming within the scope of the appended claims are embraced thereby.

I claim:

- 40 1. A hat composed essentially of an S-shaped constructional element which in extended form comprises a sinuous body portion of progressively increasing width, the widest end of said element terminating in a rounded end having a margin at a sharp angle to the adjacent concave marginal edge of the body portion, the margin of said rounded end being attachable to the adjacent margin of the body portion to form the crown of a hat.
- 50 2. A hat composed essentially of an element made of sheet material, said element, in extended and flattened form, being of generally S-shape provided with rounded ends extending in opposite directions and a sinuous body portion, said body portion being of progressively increasing width, and connecting means carried by the element in cooperating relation whereby the element is adapted to be worn as a hat when said connecting means are in engagement and the element may be extended into substantially flat form when the means are disengaged.
- 60 3. A hat composed essentially of an element made of sheet material, said element, in extended and flattened form, being of generally S-shape provided with rounded ends extending in opposite directions and a sinuous body portion, said body portion being of progressively increasing width, and connecting means carried by the ends of the element on the same side thereof whereby the element is adapted to be worn as a hat when said connecting means are in engagement and the element may be extended into substantially flat form when the means are disengaged.

4. A constructional element for headwear, said element being made of pliable sheet material, said element in extended and flattened form being of generally S-shape and provided with rounded ends, one of said ends being larger than the other and a sinuous body portion connecting said ends, said sinuous body portion being of progressively increasing width from the smaller to the larger end, said sinuous portion being provided with marginal edges each in the form of a reverse curve, the rounded end portions extending in opposite directions from such marginal edges, each of said rounded end portions extending in opposite directions from such marginal edges, each of said rounded end portions including a margin at a sharp angle to the adjacent concave section of the reverse curve; and connecting means carried by the rounded end portions, said connecting means upon engage-
